SYSTEM OF ROTATING WINGS CONTROLLED BY AN AUTOMATIC RUDDER

Giovanni Serragli, Florence, Italy

Application July 20, 1933, Serial No. 681,234
In Italy August 22, 1932

6 Claims. (Cl. 244—19)

The object of the present invention is a system of rotating wings or gyroplane which may be utilized as an autogyroplane, but which in the ordinary flight conditions, may be arrested thus producing only a small aerodynamic effect which is not detrimental to the penetration of the aircraft on which it is applied.

The general object above mentioned is obtained in this case in an automatic manner by means of a small rudder connected to one of the blades of the propeller. In addition, its mounting on the aircraft is made in accordance with such principles that ensure the best possible aerodynamical effect, eliminating at the same time the disadvantage to the stability that the aircraft would be liable to receive owing to the action of the gyroplane.

In the drawing:

Fig. 1 shows the propeller in plan,
20 Figures 2 and 3 show details of the automatic rudder, and

Figs. 4 and 5 the arrangement of the parts, in end view and in plan respectively.

The gyroplane comprises four blades 1, 2, 3, 4 (Fig. 1) which however could be reduced to two only (2—4).

All the blades have their angles of connection to the hub very small, this being a necessary characteristic for ensuring satisfactory working; the said angle may however be slightly varied along the radius.

The blades 1 and 3 are equal both in their form and lengths, and are slightly tapered towards their outer ends. The blades 2 and 4 differ on the contrary from each other, blade 2 being substantially shorter, wider and thicker than blade 4 (Fig. 1), 2 and 4 forming together a single unit which on its whole has a good aerodynamical penetration, their dimensions being selected in such a way as to realize the so called "streamline" form, while maintaining the blade form. By providing suitable counter-weights inside the blades, the necessary coincidence of the centre of gravity with the axis of rotation of the propeller is obtained, or the solid end of the blade 2 may be made with wood (as shown) and the rest may be made hollow.

The blade 4 is provided with the automatic rudder 5 consisting of a small flat piece, having 50 a rectangular or trapezoidal rounded shape 5' in plan, or any other form. Its dimensions may be varied greatly. The rudder 5 may also be very large, in which case the size of blade 4 to which it is connected may be proportionately reduced; it would also be possible to eliminate this latter

and to substitute it by a very large and elongated rudder 5 or by a blade having a variable twist.

The small flat piece can rotate round a shaft 6 rigidly connected to the blade 4. This can be 60 accomplished in any known way. The shaft 6 has an enlarged head 7 for taking up the thrust so as to hold the small flat piece when, during the rotation of the propeller, the former is urged in the radial direction; any longitudinal 65 sliding movement is thus prevented.

Fig. 3 shows the section of the flat piece 5 (hatched section) and that of the blade 4 (not hatched section). As shown, the angle of connection of the blade to the hub is small. The 70 small flat piece 5 can rotate freely round the shaft 6 but its movement is limited by suitable projections or stop teeth (not shown) to two extreme positions, which are the following:

(1) The small flat piece 5 assumes the same 75 inclination or angle of incidence as the blade 4 (viz; a very small angle). In this case it constitutes a continuation of blade 4 so that the two sections (hatched and not hatched) shown in Fig. 3 would be superposed.

(2) The small flat piece 5 assumes the position indicated in Fig. 3, or an angle of incidence α from 10° to 30° with respect to the section of the blade 4 (not hatched section) more or less, according to cases.

As already explained, the piece 5 may oscillate freely between the two limiting positions above said, but on reaching said positions it is stopped by projections or stop teeth, which are not shown in the figure, but which can easily 90 be provided.

Inside the blade 4 a small bolt or movable stop tooth 8 is also provided, which includes a small mass 9. This bolt or stop tooth slides in suitable guides and can enter a recess 10 provided in the 95 flat piece 5 when this latter is in the first limiting position above described, forming a body with the blade 4; in this position the bolt 8 prevents absolutely the rotation of the piece 5 round the spindle 6. Normally however, the bolt is kept 100 retracted and is maintained completely within the blade 4 by means of a small spring 11 as shown in Fig. 2.

The gyroplane is mounted on the aircraft and kept in position by means of four stays 12, 13, 14, 15 (Figs. 4 and 5) consisting of hollow tubes made of steel or of other suitable materials. These stays are arranged crosswise, as shown in the view of Fig. 5, where are seen in plan the points of junction of the tubes on the fuselage 110

of the aircraft, the arrow 16 indicating the direction of advancement of the aircraft which corresponds also to its traction axis.

The stays or tubes are united at their upper ends (Fig. 4 shows only the stays 12 and 14 for clearness) and carry a horizontal pivot 17 round which the axis of rotation 00 of the gyroplane can rotate. This axis is materially formed with a tube which is flattened at its lower end, forming a flat head 18 which can slide into a curved metal guide 19 the ends of which are connected directly to the stays 12 and 14 respectively, and indirectly by means of the connecting rods 20—21 to 13 and 15 respectively.

15 To the end of the flattened head 18 which extends below the guide 19 to a convenient point, two metallic cables 22—23 are fixed, which can be united by means of suitable pulleys, to one single control cable within easy reach of the pilot 20 who is thus enabled to regulate the inclination of the axis of rotation of the propeller between the two extreme positions previously mentioned, viz to the position (1), in which case the axis of the propeller is normal to the axis of the fuselage of 25 the aircraft, and to the (2) position when the said axis is inclined rearward from 30° to 40° in which case the tube 00 rests on the stay 12.

The device is placed at such a depth that the centre of gravity of the aircraft on which the 30 gyroplane is applied (generally an aeroplane) is positioned within the angle formed by the two directions of the axis of rotation indicated by the positions (1) and (2) above mentioned, and which is shown approximately by the point G, 35 in Fig. 4. The device, comprising the stays 12—14 and the other parts, described above is enclosed in a suitable casing 24 (shown by the dotted line in Fig. 5) so as to produce a sector having a stream line shape, adapted to increase 40 the aerodynamical penetration of the whole device. The sector comprises the pivot 17 as well as the whole triangle having as sides 12—14 up to the dorsal line $m-m$ of the fuselage. The stays 13—15 and the rods 20—21 are provided 45 with the usual aerodynamical casings.

The device, as far as it relates to its installation on the aircraft in the transverse direction, is disposed in such a way that the gyroplane, both for the displacement of its whole unit and for the 50 different lengths assigned to the rods 20 and 21, is placed slightly to the right or to the left of the traction axis of the aircraft (viewed from the top) according to whether the gyroplane rotates anti-clockwise or clockwise. If the gyroplane rotates in the direction indicated by the arrow 25 (Fig. 1) its mounting on the aircraft must be made slightly to the right as shown in Fig. 5. If the rotation occurs in the opposite direction, the mounting must be made slightly to the left.

60 With regard to the disposition of the various controls etc. any known mechanical means may be used, which is not shown on the drawing.

It is preferable to insert buffers at the points marked 26—27 on Fig. 5 in order to reduce the 65 shock due to the impact of the head piece 18.

The working of the device is as follows:

When the gyroplane is in the position above described (as shown on Fig. 4) viz with its axis perpendicular, or nearly perpendicular to the fuselage, the rudder 5 has the effect of causing it to 70 shift in the position shown in Fig. 1; viz the gyroplane assumes the form of a small aeroplane having as fuselage 2—4 and 1—3 as wings.

The section of the flat piece 5, or other equivalent member, possesses the known aerodynamical

characteristic of having the centre of pressure disposed in advance to the centre of the said section, so that if the plane 5 (Fig. 3) is struck by the lateral wind 28 from the right, or 29 from the left, the resultants from the aerodynamical effect 30 or 31 respectively, are always placed in advance of the centre of the spindle 6 so that in any case the small plane is fixed by the relative moments in the position described under the end position marked 2°, corresponding to that shown on Fig. 3, so that it is pressed in any case against the relative stop tooth. Under this condition the flat piece 5 acts as a vertical rudder, and as such, it causes a lateral dynamical effect which tends always to stabilize the propeller in the position shown in Fig. 1, viz with the axis 2—4 parallel to the direction of advancement V. This effect has been claimed and is covered by the United States Patent No. 1,811,867 granted to the same applicant. The gyroplane works thus as a small fixed surface which does not cause any disturbance to the normal advancement of the airplane.

Supposing now that the trajectory of the airplane becomes inclined downwards, which occurrence may be caused either by the fall of the 100 apparatus, or by the pilot causing it to descend with a steep gradient (with the inclination control), it is easy to see in this case that when the said inclination has reached a certain value, the aerodynamical effect on the piece 5 ceases to be 105 lateral, as shown by the arrows 28 and 29 in Fig. 3, but the rudder is struck from below in the direction indicated by the arrow 31. In these conditions the flat piece 5 straightens itself automatically, assuming the position described above 110 under (1) viz forming one single body or a continuation of the blade 4. In these conditions the rudder effect of the piece 5 ceases to be operative, and the system becomes a very effective self rotating propeller which gives a very substantial 115 braking action. In order to ensure that during the said auto-rotation the plane 5 remains in the desired position, the spring 11 provided on the bolt placed into the blade P₄ is adjusted so that it becomes depressed by the centrifugal force after 120 a certain number of revolutions, allowing the bolt 8 to enter the recess 10, thus forming a rigid connection between the rudder 5 and the blade 4.

When the trajectory of the aircraft ceases to be 125 inclined, on the apparatus resuming its horizontal flight, the propeller decreases its speed of rotation and the action of the spring prevails again against the effect of the centrifugal force; this has the effect of retracting the bolt inside the blade 4 thus 130 releasing the flat piece 5 which under the action of the lateral wind (28 or 29) resumes its position as shown in Fig. 3 in which it operates as a vertical rudder, stabilizing again the gyroplane in the position shown in Fig. 1 as heretofore described.

135 The rudder ensures, in the manner above described, the automatic change from the fixed propeller trim to the autorotation trim and conversely without any intervention on the part of the pilot, who may eventually be called only to regulate the inclination of axis 0.0.

The position of the installation in relation to the centre of gravity G is effected as shown on Fig. 4, as it is convenient and self evident that the gyroplane, when in its autorotating phase, 145 should give rise to a couple that tends to lift up the apparatus (anti-reversing couple) which is advantageous on landing for opposing often occurring contrary actions which are dangerous to safety. The side displacement is in the direc- 150

tion indicated on Fig. 5 as a self rotating propeller does not possess generally a centre of pressure coinciding with the axis of rotation; the said centre being placed slightly to the right or to the 5 left, according to the direction of rotation.

If a propeller is mounted in the central position, a side drift of the aircraft would be produced. This inconvenience is eliminated by mounting the propeller in the position shown in 10 Fig. 4, in which the aerodynamical resultant of all the forces acting on the propeller, coincides with the axis of thrust, thus eliminating all side or healing actions.

As the blades 2 and 4 have different lengths, 15 it may happen that in certain conditions of working they may produce inconveniences due to vibrations, owing to the different moment of thrust they transmit to the hub of the propeller. This inconvenience may be overcome by setting the 20 blade 4 (the longer blade) with an angle of incidence greater than that of blade 2 (the shorter blade). Thus the incidence of the blade 4 becomes reduced, as well as its aerodynamical effect, which latter, through suitable calculations, may 25 be made equal to that of blade 2 thus ensuring the necessary balance.

The control for the inclination of the axis 0—0 operates in a manner which need not be explained in detail. It will only be sufficient to explain in 30 this connection that it is preferable to use a rope control instead of any rigid control, in order to eliminate all vibrations.

The pilot may use with advantage the gyroplane in auto-rotation when an exceptional value 35 of the lift becomes necessary, as also in the case of taking off, of landing, or in flying at slow velocity.

I claim:

1. System of rotating wings for the aerodynamical braking of aircraft during their descent, or in all cases when an additional support is required, an axle, said system being mounted loose on said axle which is in ordinary conditions perpendicular to the axis of the fuselage of the aircraft, formed with four blades or wings mounted on to the axle with a very small or null angle of incidence, two of said blades or wings being equal to each other, and having a slightly decreasing width towards their outer ends, the other two 50 blades or wings being of different lengths, width and thickness, one being wider, shorter, and thicker with respect to the other, forming together a body having a good aerodynamical penetration; an automatic rudder being provided at the outer 55 end of the longer blade formed with a flat plate the inclination of which is variable, this flat plate acting as a vertical rudder when the direction of the advancement of the aircraft lies in the plane of rotation of the blades, but ceasing to 60 act as such when the trajectory of the aircraft inclines downwards, either owing to the fall or to a voluntary steep gradient of descent.

2. System of rotating wing according to claim 1, in which the small automatic rudder adjusts itself in the preferred position, and means to lock the rudder in adjusted position, consisting of a tooth or bolt actuated by centrifugal force.

3. System of rotating wings for the aerodynamical braking of aircraft during the descent thereof, or in all cases when an additional support is required, an axle, said system being loosely mounted on said axle which has a hub and is in ordinary conditions perpendicular to the axis of

the fuselage of the aircraft, formed with four blades or wings mounted on the hub with a very small or null angle of incidence, of which blades or wings two are equal to each other, while the other two blades or wings are of different length, width and thickness, one of the latter being wider, shorter, and thicker than the other, an automatic rudder provided at the end of the longer blade and formed with a flat piece having a variable inclination and which acts as a vertical rudder when the direction of advancement of the aircraft coincides with the plane of rotation of the blades, but ceases to act as such when the trajectory of the aircraft inclines downwards, whereupon said automatic rudder adjusts itself and is automatically locked in predetermined position, the axle on which the rotating wings are loosely mounted being both adapted to rotate round a horizontal pivot supported by four stays fixed on the fuselage of the aircraft, and enclosed in a casing having an aerodynamical outline, the rotation of said axle being controlled by the pilot by means of metallic cables, while the inclination of the axis of rotation is made to vary from naught to 30 and even to 40 degrees.

4. System according to claim 3, wherein the rotating wing device which includes the axle with its hub and the wings or blades as well as the small automatic rudder, is mounted on the fuselage so that the centre of gravity of the aircraft both is comprised within the angle formed by the two extreme limiting positions of the rotating wing, viz from 0° to 30°-40°, and is in addition displaced slightly to the right or to the left, so that the centre of the aerodynamical pressure of the wing may coincide with the axis of thrust of the aircraft.

5. System according to claim 3 wherein the two blades having different length, width and thickness are mounted on the hub with different angles of incidence, in order to transmit thrusts of substantially equal intensity to said hub.

6. System of rotating wings for the aerodynamical braking of aircraft during the descent thereof, and in all cases when an additional support is required, an axle on which said system is loosely mounted said axle provided with a hub and in normal conditions disposed perpendicular to the axis of the fuselage of the aircraft, and which system is formed with four blades or wings connected to said hub with a very small or null angle of incidence, of which blades or wings two are both opposite and equal to each other, while the other two blades or wings are of different length and width and one of the latter being wider and shorter than the other, which blades or wings together form an efficient aerodynamic body, an automatically operating rudder pivotally mounted at the outer end of the longer of said two different blades or wings and formed with a practically flat plate adapted to be inclined at various angles, which flat plate acts as a vertical rudder when the direction of the advancement of the aircraft practically coincides with the plane of rotation of the blades, but ceases to act as a rudder when the trajectory of the aircraft for any reason inclines downward, and centrifugally operated automatic means locking said plate in predetermined aligned position with respect to said longer blade or wing during such rotation of said blades or wings.

GIOVANNI SERRAGLI.
